MATERIAL GATHERING AND LOADING MACHINE

Chester E. Andershock, Chicago, Ill., assignor to
Goodman Manufacturing Company, Chicago,
Ill., a corporation of Illinois

Application August 14, 1944, Serial No. 549,389

3 Claims. (Cl. 198—8)

This invention relates to improvements in material gathering and loading machines of the type adapted to load coal at the working face of a mine underground.

Heretofore face loading machines mounted on continuous tread devices or mounted for loading from a track have been provided with an inclined elevating conveyer extending in advance of the main frame of the machine and pivotally connected to the main frame for movement about a transverse axis. A gathering head has been mounted at the forward end of the elevating conveyer, for picking up material from the ground and loading it onto the elevating conveyer. Screw devices or hydraulic cylinders and pistons connected between the main frame and the underside of the elevating conveyer have been used for raising or lowering the gathering head by power about the axis of pivotal connection of the elevating conveyer to the main frame. Since these cylinders and pistons or screw devices have been disposed beneath the elevating conveyer, usually in advance of the pivotal axis of the conveyer, they have obstructed travel of the machine over an uneven mine bottom and have made it difficult, if not impossible, to load over rough and uneven bottoms and along benches on the floor, especially where the machine is mounted on continuous tread devices and is constructed for operation in thin seams of coal.

My invention has as its principal objects to overcome these difficulties by providing a new, improved and simplified means for elevating the gathering head of a low vein loading machine, so arranged as to be free from the ground so as to provide an unobstructed space between the underside of the gathering head and the ground at the axis of pivotal movement thereof.

A more specific object of my invention is to provide a novel form of elevating means for the gathering head of a low type loading machine which is disposed above the transverse pivotal axis about which the gathering head is elevated, but which is beneath the upper extremities of the machine, in all positions of adjustment of the gathering head, so as to maintain the low overall dimensions of the machine to the minimum height required for operation in thin seams of coal.

My improved form of means for vertically moving the gathering head of a loading machine, which constitutes the inventive subject matter of the present application, is disclosed but not claimed in an application Serial No. 497,004, filed by Frank Cartlidge on August 2, 1943, and

entitled improvements in Material gathering and loading machines, and assigned to the assignee of the present application.

Other objects of my invention will appear from time to time as the following specification proceeds and with reference to the accompanying drawings wherein:

Figure 1 is a top plan view of the front part of a loading machine constructed in accordance with my invention, with certain parts broken away and certain other parts shown in substantially horizontal section;

Figure 2 is a view in side elevation of the front part of the loading machine shown in Figure 1, showing the gathering head in one position of adjustment;

Figure 3 is a view somewhat similar to Figure 2, but showing the gathering head in an elevated position;

Figure 4 is an enlarged detail view showing certain details of the yieldable means for urging the gathering head into an elevated position; and

Figure 5 is a longitudinal sectional view taken through one of the cylinders for elevating the gathering head.

In the drawings, the loading machine consists generally of a main frame 10 mounted on a pair of laterally spaced continuous tread devices 11, 11 and having an inclined gathering element or head 12 disposed in advance of said main frame and mounted for vertical adjustment with respect thereto about a transverse axis. A conveyer 13 has said gathering head mounted at its forward end and extends from said gathering head in an upwardly inclined direction to and over said main frame and beyond the rear end of the latter in an overhanging position (not shown), so as to discharge material into mine cars or the like. The detailed construction of said loading machine is clearly disclosed in the aforementioned application Serial No. 497,004, so will not herein be shown or described in detail.

The gathering head 12 is supported in advance of the main frame 10 for lateral movement with respect thereto and for vertical adjustment with respect thereto on a laterally movable frame 14, which is mounted at the forward end of said main frame for pivotal movement about the vertical axis of a bearing boss 17 (see Figure 1). Said laterally swinging frame rests on and slidably moves along a forwardly projecting bottom supporting plate 18 of said main frame and extends in advance of the forward end of said main frame. A cylinder and piston indicated generally by reference character 19 are provided

to laterally swing said frame and gathering head in a well known manner. The detailed construction of said frame and its vertical pivotal connection to said main frame are no part of my present invention and are clearly shown and described in the aforementioned application Serial No. 497,004, so are not herein shown or described in detail.

The gathering head 12 is mounted on the forward end of a longitudinally extending inclined frame 21, which is transversely pivoted to the forward end of the swinging frame 14. The upper portion of said inclined frame 21 forms an inclined trough for the inclined elevating portion of the conveyer 13. Said inclined frame is transversely pivoted adjacent its rear end on the forward end of the laterally swinging frame 14, on the outer peripheries of bearing bosses 22, 22 formed integrally with the frame 14, the insides of which bosses form bearing supports for a transverse drive shaft 23 for a chain 24 for the conveyer 13, and which drive shaft is coaxial with the horizontal pivotal axis of said inclined frame 21.

The gathering head 12, herein shown, is of a well known form of endless chain gathering head and includes an inclined apron 25 mounted on the forward end of the inclined frame 21 and extending in advance thereof and across the front end of the conveyer 13. A pair of chain guiding members 27, 27 having endless chains 28, 28 guided for orbital movement thereabout are mounted on the top side of said apron, as usual, so as to extend along opposite sides of and forwardly of said conveyer. A plurality of gathering arms 29, 29 are carried by said endless chains for picking up material from the ground and moving it along a forward portion of said apron onto the conveyer.

The conveyer 13 is herein shown as being of the single strand laterally flexible type having a plurality of flights 31, 31 pivotally connected to adjacent ends of sections of the chain 24 so said chain will flex laterally upon lateral flexible movement of the forward or discharge ends of the conveyer, as is well known to those skilled in the art. Said chain and flights extend from an idler 32 mounted at the forward end of the inclined frame 21, upwardly along said frame in a trough formed by opposite side walls thereof, and over the top of said main frame in a trough formed by flexible side walls 33, 33, as is clearly shown and described in the aforementioned application of Frank Cartilage, Serial No. 497,004, so not herein shown or described in detail.

Referring now in particular to the novel means for elevating the gathering head 12 and the forward end of the conveyer 13 about the axis of the drive shaft 23, a pair of laterally spaced cylinders 35, 35 extend along opposite sides of said conveyer in a generally horizontal plane when the gathering head 12 is in a lowered position (see Figures 1 and 2). Each of said cylinders has a piston 36 slidably mounted therein with a piston rod 37 secured thereto and extending from said cylinder (see Figure 5). Said cylinders each have ports in the head and piston rod ends thereof so as to supply fluid under pressure to either end of said cylinder, so said pistons and piston rods may positively raise or lower said gathering head by power.

Each cylinder 35 has a plurality of spaced ears 39, 39 extending rearwardly from its head end. Said ears extend along opposite sides of a bracket 40, projecting upwardly from and herein shown

as being formed integrally with the swinging frame 14 and disposed to the rear of the axis of vertical adjustment of the forward end of the conveyer 13 and gathering head 12. Pivotal pins 41, 41 pivotally connect said ears to said brackets. The free end of each piston rod 37 is pivotally connected to a bracket 43 by means of a pivotal pin 44. Said brackets are disposed forwardly of the axis of vertical adjustment of the conveyer 13 and are mounted on plates 45, 45 projecting outwardly from the sides of the inclined frame 21, just rearwardly of and beneath the upper end of the inclined apron 25.

A pair of pre-loaded compression springs 47, 47 are provided to exert a force on the gathering head 12 in a direction to tend to hold it in floating engagement with the ground when pressure is relieved from the head and piston rod ends of the cylinders 35, 35. Said springs extend along opposite sides of the conveyer and encircle eyebolts 48, 48 transversely pivoted to bifurcated brackets 49, 49. Each bracket 49 extends upwardly from the plate 45 and is spaced outwardly from and forwardly of the bracket 43. The opposite end of said eyebolt is threaded in a flanged sleeve 50, the flange of which sleeve is abutted by the rear end of said spring 47. The flange of said sleeve is urged in a direction towards an abutment member 51 by means of said spring, which abutment member is transversely pivoted to a bracket 54, projecting upwardly from the upper end of the laterally swinging frame 14. The opposite end of said spring abuts a flanged sleeve 55, which encircles said eyebolt 48 and permits said eyebolt to slidably move with respect thereto. Said abutment member 51 and flanged sleeve 55 are connected together by means of a plurality of threaded rods 56, 56 threaded at their ends in the flanges of said sleeves and abutment members. Said rods also extend through the flange of the flanged sleeve 50 and form a slidably guide therefor. Nuts 57, 57, threaded on opposite ends of said rods, lock said rods to the flanges of said sleeves.

It may be seen from the foregoing that lowering of the gathering head 12 will compress the springs 47, 47. Said springs will thus exert a force on said gathering head 12 through the flanged sleeves 50, 50 and eyebolts 48, 48, in a direction to tend to move said gathering head in an upward direction. When said gathering head is in an elevated position and fluid under pressure is relieved from the piston rod ends of the cylinders 35, 35, said springs will retard downward movement of said gathering head and will prevent it from hitting the ground with a sharp blow.

It may here be seen that said cylinders and their piston rods are disposed above the axis of pivotal movement of the inclined frame 21 and the gathering head 12, so that an unobstructed space is provided between the underside of said inclined frame and the ground, to provide clearance between the underside of said gathering head and the ground, at the point of pivotal movement thereof, and are so arranged as not to add to the vertical height of the machine.

It may also be seen that this arrangement removes all obstructions from underneath the gathering element and the inclined elevating portion of the conveyer, and provides sufficient clearance to permit the machine to pick up material from the ground, where the bottom is rough or irregular, or where the gathering element is loading 75 from a bench spaced above the bottom proper,

or is loading over obstructions on the mine bottom.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a low type loading machine, a main frame, a pair of laterally spaced continuous tread devices for supporting said main frame for movement along the ground, a swinging frame projecting forwardly of the forward end of said main frame and mounted thereon for horizontal swinging movement about a vertical axis, an elevating conveyer pivotally mounted on said swinging frame, adjacent the forward end thereof, for pivotal adjustment about a transverse axis disposed in advance of said main frame, said conveyer having a gathering head on the forward end thereof and extending upwardly at an inclined angle from a point in advance of said swinging frame to and along said main frame, means for laterally moving said swinging frame and conveyer with respect to said main frame for positioning said gathering head to one side or the other of said main frame, two double acting fluid pressure cylinders and pistons for elevating or lowering said gathering head and conveyer about said transverse axis, each of said cylinders and pistons extending along one side of said conveyer above the pivotal axis thereof but within the upper limits of the side walls of said conveyer, when the gathering head is in a depressed position, said cylinders and pistons having pivotal connection with said swinging frame and the forward portion of said conveyer, on opposite sides of the axis of pivotal connection of said conveyer to said swinging frame, and yieldable means extending along opposite sides of said conveyer and disposed above said pivotal axis and pivotally connected between said swinging frame and said conveyer for urging said gathering head in an elevated position and for holding it in floating engagement with the ground when fluid under pressure is relieved from said cylinders and pistons.

2. In a low type loading machine, a main frame, a pair of laterally spaced continuous tread devices for supporting said main frame for movement along the ground, a swinging frame projecting forwardly of the forward end of said main frame and mounted thereon for horizontal swinging movement about a vertical axis, an elevating conveyer pivotally mounted on said swinging frame, adjacent the forward end thereof, for pivotal adjustment about a transverse axis disposed in advance of said main frame, said conveyer having a gathering head on the forward end thereof and extending upwardly at an inclined angle from a point in advance of said swinging frame to and along said main frame, means for laterally moving said swinging frame and conveyer with respect to said main frame for positioning said gathering head to one side or the other of said main frame, two double acting fluid pressure cylinders and pistons for elevating or lowering said gathering head and conveyer about said transverse axis, each of said cylinders and pistons extending along one side of said conveyer above the pivotal axis thereof but within the up-

per limits of the side walls of said conveyer, when the gathering head is in a depressed position, said cylinders and pistons having pivotal connection with said swinging frame and the forward portion of said conveyer, on opposite sides of the axis of pivotal connection of said conveyer to said swinging frame, and yieldable means extending along opposite sides of said conveyer and disposed above said pivotal axis and pivotally connected between said swinging frame and said conveyer for urging said gathering head in an elevated position and for holding it in floating engagement with the ground when fluid under pressure is relieved from said cylinders and pistons, each of said yieldable means including a member pivotally connected to said swinging frame a substantial distance to the rear of the axis of vertical pivotal movement of said conveyer, another member pivotally connected to said conveyer a substantial distance in advance of the axis of vertical pivotal movement of said conveyer and having slidable connection with said first mentioned member, and a compression spring interposed between said members.

3. In a low type loading machine, a main frame, a pair of laterally spaced continuous tread devices for supporting said main frame for movement along the ground, a swinging frame projecting forwardly of the forward end of said main frame and mounted thereon for horizontal swinging movement about a vertical axis, an elevating conveyer pivotally mounted on said swinging frame, adjacent the forward end thereof, for pivotal adjustment about a transverse axis disposed in advance of said main frame, said conveyer having a gathering head on the forward end thereof and extending upwardly at an inclined angle from a point in advance of said swinging frame to and along said main frame, means for laterally moving said swinging frame and conveyer with respect to said main frame for positioning said gathering head to one side or the other of said main frame, two double acting fluid pressure cylinders and pistons for elevating or lowering said gathering head and conveyer about said transverse axis, each of said cylinders and pistons extending along one side of said conveyer above the pivotal axis thereof but within the upper limits of the side walls of said conveyer, when the gathering head is in a depressed position, said cylinders and pistons having pivotal connection with said swinging frame and the forward portion of said conveyer, on opposite sides of the axis of pivotal connection of said conveyer to said swinging frame, and yieldable means extending along opposite sides of said conveyer above said transverse pivotal axis and extending along the outer sides of said cylinders and pistons for urging said gathering head in an elevated position and holding it in floating engagement with the ground when fluid under pressure is relieved from said cylinders and pistons, said means each including a member pivotally connected to said swinging frame a substantial distance to the rear of the axis of pivotal movement of said conveyer and extending beyond the forward end of said swinging frame, another member pivotally connected to said conveyer a substantial distance in advance of the transverse pivotal axis thereof, a slidably supporting and guiding connection between said members, and a compression spring interposed between said members.

CHESTER E. ANDERSHOCK.
